C. Snowdon.

UNITED STATES PATENT OFFICE.

JOHN ASHTON, OF LAWRENCE, MASSACHUSETTS.

LOCK-HINGE.

SPECIFICATION forming part of Letters Patent No. 530,877, dated December 4, 1894.

Application filed November 20, 1893. Serial No. 491,453. (No model.)

To all whom it may concern:

Be it known that I, JOHN ASHTON, a citizen of the United States, residing at Lawrence, in the county of Essex and State of Massachusetts, have invented a new and useful Lock-Hinge, of which the following is a specification.

This invention relates to lock-hinges; and it has for its object to effect certain improvements in hinges of that class which are suitable for blinds, gates, doors, and other moving objects and which not only provide for hinging such objects to their stationary casings or frames, but at the same time provide means for locking the objects in an open or closed position, thereby dispensing with supplemental fastenings.

To this end the main and primary object of the present invention is to simplify and render more efficient hinges of this type.

With this and other objects in view which will readily appear as the nature of the invention is better understood, the same consists in the novel construction, combination and arrangement of parts hereinafter more fully described, illustrated and claimed.

In the drawings:—Figure 1 is a perspective view of a portion of a window casing and blind showing my improved lock-hinge applied thereto. Fig. 2 is a detail in perspective of the lock-hinge unattached. Figs. 3 and 4 are similar views of the hinge leaves or members. Fig. 5 is an enlarged detail plan view of the lock hinge showing a modification of one of the hinge members.

Referring to the accompanying drawings, A represents a portion of a window casing and B a portion of a blind hinged thereto, and as illustrated in Fig. 1 of the drawings 40 the blind B, is to be hinged to the casing by an upper hinge of the ordinary construction, and the lower lock hinge D, constructed in accordance with the present invention, but it will of course be understood that the position of these hinges may be reversed, or the lower lock hinge attached to any other moving object than a window blind or shutter B.

The lock hinge D, comprises the separate hinge members or leaves E and F, which are 50 adapted to be interlocked to secure the proper hinging of the moving object to its casing or frame. The hinge member or leaf E is pro-

vided with an attachment or base plate G, which is adapted to be attached to the frame or casing A, and from which is projected at 55 right angles the leaf arm H. The leaf arm H, of the hinge member or leaf E, projects a distance beyond the attachment or base plate G, of which it forms an integral part, and is provided near its outer end with the pintle 60 opening I, which pintle opening is intersected at the top by the transverse lock groove J, and is provided at one side with the vertical guide groove K.

The transverse lock groove J is formed in 65 the top face of the leaf arm H, and extends beyond both sides of the pintle opening I, and at direct right angles to the longitudinal disposition of the leaf arm to provide for the locking of the moving object in its opened or closed position as will be more particularly referred to, and the said leaf arm H, is further provided, beyond the pintle opening and at one side of the transverse lock groove, with a flat bearing lip L, on which rides the under 70 side of the moving hinge member or leaf F, when the same is being turned to a locked position.

The hinge member or leaf F, is provided with an attachment plate M, adapted to be 80 attached to the blind B, or other moving object, and from which plate is projected the pintle arm N. At the outer extremity of the pintle arm is located the hinge pintle O, disposed at right angles to the pintle arm and 85 adapted to engage the pintle opening I, of the other hinge member or leaf, and said pintle is provided at one side and its lower extremity with the retaining stud P, which is 90 adapted to engage the guide opening K, when the hinge members are being placed together or taken apart, and for the said stud to be brought in alignment with the guide grooves it is necessary to turn the member F, to a 95 position at direct right angles to the transverse lock groove J.

The pintle arm N, of the hinge member or leaf F, is further provided at its under side with a narrowed projected locking lug Q, 100 which is disposed longitudinally of the pintle arm and is adapted to automatically drop into engagement with the transverse locking groove J, when brought into alignment therewith at either side of the pintle opening, I.

To open or close the blind B, or other moving object to which the member or leaf F, is attached, it is simply necessary to lift the object so as to raise the locking lug Q, out of the groove J. This locking lug will then freely turn on the flat bearing lip L, until it falls into the opposite portion of the locking groove when brought into alignment therewith, when the moving object is completely open or shut. When lifting the locking lug out of the locking groove the stud P, prevents the pintle O, from being lifted out of the pintle opening.

As clearly illustrated in Fig. 5 of the drawings, the pintle arm N, may be further provided with a horizontal guard flange R, of a length and width slightly greater than that of the transverse locking groove J, so that when the hinge member or leaf F, is in either locked position, the said flange will cover the locking groove to keep the same free from snow and ice, and other deposits which would interfere with the working of the hinge.

It will of course be understood that the attachment of the members or leaves E, and F, may be such that one member will be attached to the stationary object and the other to a moving object as may be required by the particular occasion, and I will further have it understood that changes in the form, proportion and the minor details of construction may be resorted to without departing from the principle or sacrificing any of the advantages of this invention.

Having thus described the invention, what is claimed, and desired to be secured by Letters Patent, is—

1. In a lock hinge, the combination of the hinge leaf or member provided with a base plate and an integral horizontal leaf arm having a pintle opening near its outer end, a transverse lock groove formed in the top face thereof and extending from edge to edge, said lock groove intersecting the pintle opening

at right angles to the disposition of the leaf arm, a vertical guide groove K, formed in one side of the pintle opening, and a flat top bearing lip L, projected beyond the outer edge of said transverse lock groove, and the other hinge leaf or member provided with an integral horizontal pintle arm provided at its under side with an integral narrowed lug or rib Q, adapted to ride freely on the flat top bearing lip L, and into engagement with the transverse lock groove at either side of the pintle opening, said pintle arm being also provided at its outer extremity with a right angularly disposed pintle turning in said pintle opening and having near its lower end a retaining stud P, adapted to pass through said vertical guide opening and to work under the leaf arm of the other member, said stud being disposed out of alignment with the vertical guide groove when the locking lug or rib is in either of its locked positions, substantially as set forth.

2. In a lock hinge the combination of the hinge leaf having a pintle opening near its outer end and a transverse lock groove, and the other hinge leaf having an integral pintle arm provided with an integral pintle engaging said pintle opening, an integral locking lug adapted to engage said locking groove, and an integral horizontal guard flange extended beyond the ends and sides of the pintle arm and of a length and width exceeding the length and width of the transverse locking groove to completely cover the same when the hinge leaves are locked together, substantially as set forth.

In testimony that I claim the foregoing as my own I have hereto affixed my signature in the presence of two witnesses.

JOHN ASHTON.
